UNITED STATES PATENT OFFICE

BENZION WOLF, OF CHICAGO, ILLINOIS

GARTER

Application filed November 12, 1928. Serial No. 318,861.

My invention relates to garters and particularly to garters which are adapted to be supported at a point adjacent and above the ankle of the wearer.

- 5 It has heretofore been common practice, particularly among men, to employ garters of an elastic type which are designed to encircle the wearer's leg at a point below the knee. Garters of this type present an elastic band
- 10 which yieldingly encircles the wearer's leg and compresses the same with sufficient force to prevent the band from being downwardly displaced when the wearer's stocking is supported thereby. Persons afflicted with enlarged veins, or persons having skin which is readily irritated by the application of elastic bands and the like, cannot satisfactorily employ garters of that type. In some instances it has been found undesirable to wear the conventional elastic band type of garter for the reason that circulation of the blood stream is impaired.

In general, one of the primary objects of my present invention is to provide a garter 25 of an anatomic nature which will positively avoid the above mentioned and other unsatisfactory results which have heretofore been experienced by wearers of known types of elastic band garters.

30 More specifically, my invention contemplates the provision of a garter which may be worn without experiencing any binding or pressure upon the wearer's leg and hence which will permit of free blood circulation.

35 Another object of my invention is to provide an anatomic garter which may be applied at a point immediately above the wearer's ankle, this being a point at which the application of a band will not affect circulation and to this end I propose to employ either an elastic or non-elastic band which may be conveniently applied.

A still further and more specific object of my invention is to provide a garter construction which consists of a band of either elastic or non-elastic material which may be applied, for example, at a point immediately above the wearer's ankle, said band being provided with one or a plurality of upwardly extending members which are adapted, at their upper

extremities, to be secured to the upper margin of the stocking, thereby providing an effective means for upholding the stocking in proper position without necessitating the use of a tightly fitting elastic band at a point 55 above the stocking.

These and other objects will be more apparent from the following detailed description of the accompanying drawing, wherein:

Figure 1 is a side elevational view disclosing the application of one embodiment of the invention to the leg of a wearer;

Figure 2 discloses the garter as viewed from the left of Figure 1;

Figure 3 is an enlarged detail view of the 65 garter shown in Figure 1;

Figure 4 is a transverse sectional view taken substantially along the line 4—4 of Figure 3;

Figure 5 is a transverse sectional view taken 70 substantially along the line 5—5 of Figure 3; and

Figure 6 is a perspective view of an alternative or modified form of garter.

Referring now to the drawing more in detail wherein I have employed like numerals to designate similar parts throughout the various figures, it will be observed that for the purpose of illustrating one embodiment of my invention, I have shown a garter indicated 75 generally by the numeral 10, Figure 3. This garter 10 includes a flexible member or band 12 which is adapted to be applied about the wearer's leg as shown in Figures 1 and 2 at a point above the ankle. The extremities of 80 the member or band 12 may be secured together in any suitable manner such as by means by a buckle 14.

Secured to the intermediate portion of the band 12 and extending laterally thereof is a 90 support member 16. In the particular embodiment disclosed, this support member 16 is arranged at substantially right angles with respect to the band 12 and comprises a pair of strips 18 and 20 which are secured together in any suitable manner as by means of stitching 22, Figures 4 and 5. The distance between the two vertical rows of innermost stitching 22 is sufficient to permit a stay or reinforcing member 24 to be inserted between 95 100

the strips 18 and 20 at the intermediate section thereof. In other words, a pocket 25 is presented intermediate the strips 18 and 20 which is adapted to receive the reinforcing member 24, the lower extremity of the strips having a stitching 26, Figure 3, extending across said pocket so as to prevent the stay or reinforcing member 24 from being displaced downwardly below a predetermined point. This pocket presented between the strips 18 and 20 is open at the upper end so as to readily allow for the insertion of the stay 24.

Secured to the upper extremity of the strips 18 and 20 is a suitable fastening device 28 which is adapted to be swung outwardly and downwardly in a position to be secured to the upper margin of a stocking 30. Thus it will be apparent that the stocking will be supported in its proper position upon the wearer through the agency of the reinforced strips of the supporting member 16. Any tendency to move the support 16 and consequently the band 12 downwardly, will be counteracted by reason of the fact that said band is positioned above the wearer's ankle. By having this construction it is not necessary to tightly encircle the wearer's leg with the band because the enlarged area presented by the ankle will be sufficient to prevent the band from slipping downwardly.

An alternative or modified form of garter is shown in Figure 6 which I have designated generally by the numeral 10^a. The only difference between the garter 10^a of Figure 6 and the garter 10 of Figure 3 is that the garter 10^a is equipped with a plurality of supporting members or strips 16. The garter 10^a may be used in instances where the stocking is subjected to considerable forces which tend to disturb the position of the stocking.

From the foregoing it will be apparent that my invention contemplates the provision of an anatomic garter which lends itself particularly adaptable for application to the lower portion of the wearer's leg. However, my invention contemplates the use of a garter of similar design in other positions. For example, the band 12 might be applied to a point above the wearer's knee and thereby render the same adaptable for use in supporting stockings of the elongated type. In this connection it is to be understood that the material comprising the band 12 and the supporting strips may be of elastic or non-elastic construction. In some instances where a close fit between the band 12 and the wearer's leg is desired, the buckle 14 may be entirely eliminated and supplanted by other suitable inconspicuous fastening devices and, if desirable, the band 12 may comprise an endless elastic band. In such instances said band may be slipped over the wearer's foot into encircling position above the ankle. The stay or supporting member 24 should be sufficiently

rigid to satisfactorily support the stocking and yet sufficiently flexible to render the same readily adaptable to conform to the contour of the leg. By having the stay 24 readily removable, the band 12 and associated strips 18 and 20, which are preferably constructed of fabric material, may be washed whenever the occasion demands. One of the outstanding advantageous characteristics of my improved anatomic garter resides in the fact that it is not secured in position solely by pressure upon the leg as is the case in known types of garters. By applying the band at a point which is least affected by pressure, the tendency for obstructing or impairing blood circulation is positively avoided. Although it is not necessary to apply pressure at a point above the wearer's ankle in order to maintain the position of the band 12, considerable pressure may be applied at this point without causing any injury or discomfort. At least the discomforts which have heretofore been experienced when the garter has been worn at a position above the upper margin of the stocking are completely obviated.

Although I have illustrated and described an embodiment of my invention which employs a particular type of means for securing the extremities of the encircling band together, as well as a particular type of device for gripping the upper margin of the stocking, it will be readily appreciated that numerous other fastening devices may be employed without departing from the spirit and scope of my invention. It might also be advisable, in certain instances, to vary the proportionate width and length of the various parts constituting the garter which would differ from that disclosed in the various figures and such variations are contemplated as being within the scope of the present invention. The reinforcing member inserted within the pocket presented between the strips 18 and 20 may be comprised of any suitable rigid yet flexible material such as whale bone or the like. It will be apparent that this reinforcing member or stay will be completely covered by the strips 18 and 20 and hence the covering strips will be the only materials which are actually brought into direct contact with the wearer's skin. By having the stay and strips constructed of proper material and by having said parts correctly shaped, said member will occupy an inconspicuous position adjacent the wearer's leg and will serve as a positive means for securing a stocking in position. In use, the band 12 of the garter is applied directly to the wearer's skin immediately above the ankle and with the supporting member 16 extending upwardly along the surface of the leg. The stocking is then pulled upwardly over the garter and the fastening device 28 swung outwardly and downwardly so as to engage with the portion of the stocking which is

forced outwardly by the button of said fastening device at a point adjacent the margin of the stocking as clearly shown in Figure 1. Thus, the only portion of the garter 5 which is not covered by the stocking is that portion of the fastening member which is swung over the upper margin of the stocking.

Having thus described my invention, what 10 I claim as new and desire to secure by Letters Patent is:

In a garment support of the class described, a flexible band adapted to be applied above and to rest upon the ankle of a wearer, a supporting member secured to and extending upwardly from said flexible band, said supporting member including an elongated fabric strip provided with an elongated pocket and reinforcing member removably 15 inserted within said pocket for lending rigidity to said supporting means, and a garment fastening device secured to the upper extremity of said supporting means and depending therefrom in a position to receive 20 the garment to be supported.

In witness whereof, I have hereunto subscribed my name.

BENZION WOLF.
